UNITED STATES PATENT OFFICE

CLARENCE J. GATES, JR., OF CHICAGO, ILLINOIS, ASSIGNOR TO CHICAGO FIBRE BOX COMPANY, OF CHICAGO, ILLINOIS, A CORPORATION OF ILLINOIS

SHIPPING CONTAINER

Application filed September 21, 1929, Serial No. 394,217. Renewed August 17, 1931.

The present invention relates to shipping containers and more particularly to that variety of shipping container adapted to be collapsed for shipment and storage, one object of the invention being to provide a simple, economical and exceedingly strong construction of container which can be shipped to the user in a flat or collapsed condition and which can be quickly and easily set up and sealed without the use of any expensive equipment, such as a stapling machine, and without requiring the additional labor which such equipment usually necessitates.

The so-called slotted carton has several outstanding disadvantages from the standpoint of economy and strength for the reason that double walls are provided in this type of container at points where they are unnecessary, thus wasting considerable material; and at points where double walls would be desirable and necessary this type of container fails to provide such reinforcement. Among the advantages of the slotted carton are the compactness with which it can be bundled when collapsed and the ease with which it can be set up, packed and sealed for shipment since no complicated and expensive machinery is required in these processes.

A further object of the invention is to provide a uniformly reinforcing container having all of the advantages of the so-called slotted carton in that it will be collapsible and easy to set up and seal, and also will have the further advantages of being able to safely carry a weight per unit of volume substantially twice the weight now permitted by the freight classification committees to be carried in slotted cartons.

A still further object is to provide a container which readily adapts itself for use with reinforcing bands and in which no further sealing means other than reinforcing bands are required.

To these and other ends the invention resides in certain improvements and combinations of parts, all as will be hereinafter more fully described, the novel features being pointed out in the claims at the end of the specification.

Referring more particularly to the drawings:

Fig. 1 is a perspective view of the container of the present invention as it appears when set up ready for packing;

Fig. 2 is a perspective view of the container as it appears after being packed and sealed ready for shipment; and

Fig. 3 is a view of the container in a collapsed condition.

Similar reference numerals throughout the several views indicate the same parts.

The invention, as herein disclosed, comprises a container made up of four blanks which are formed so as to reduce the waste to a minimum and in which the blanks are secured together in such a way as to provide reinforced corners and also are secured in such a manner as to adapt the container to be collapsed flat for convenient shipment.

Referring more in detail to the drawings the container is illustrated as comprising two body blanks 5, 5 and two end blanks 6, 6. Each body blank 5 comprises a side wall 7 and a closure flap 8 at each side thereof. The corresponding closure flaps 8, 8 of each body blank 5 cooperate to form top and bottom closures for the container. In the present instance the cooperating closure flaps 8, 8 are disclosed as somewhat overlapping but obviously they may be of such length as to just meet at the center of the container or they may be made sufficiently long to more completely overlap each other.

The end blanks 6, 6 are preferably identical as in the case of the body blanks 5, 5. Each end blank is preferably formed with a substantial flap at each side thereof, two of the flaps being indicated at 9, 9 and the remaining two being indicated at 10, 10.

The flaps 9, 9 are preferably secured to the inside surface of the side walls 7, 7 by suitable means such as staples 11 (see Figs. 1 and 3). After the blanks have been secured together at the box factory in this manner it will be evident that the container is in readiness to be collapsed as clearly shown in Fig. 3. In this condition the closure flaps are all extended so as to lie substantially in the plane of their adjoined walls and the thick-

ness of the collapsed container will at no point be greater than substantially three thicknesses of the material from which it is made. After the container reaches the user it is a simple matter to set it up ready for packing. The flaps 9, in overlapping the side walls and being secured thereto, provide a much stiffer vertical corner for the container to thus prevent injury to the contents of the container by reason of heavy loads being placed upon it and also tend to prevent collapse of the corners inwardly in case of a heavy object falling against the corners during shipment. This construction also permits the containers to be stacked to a considerable height without danger of the lower ones collapsing under the load.

With the container set up as shown in Fig. 1, so that the lower flaps 10, 10 and 8, 8 are bent over to close the bottom, the container will then be ready to be packed. After the container has received its load the top flaps 10, 10 on the end walls 6, 6 are bent over at right angles to the end walls and the side wall flaps 8, 8 are also swung downwardly into place. The container is now ready to be sealed in closed condition.

In the present instance the sealing of the container is accomplished by the use of metal straps 12, 12 and 13, 13. The metal straps 12, 12 extend around the bottom and side walls and over the top of the container and the ends of the straps are secured together with a metal seal 14. The metal straps 13, 13 extend around the side and end walls and are likewise secured with metal seals.

In certain instances it has been found desirable to glue together the overlapping edge of flaps 8, 8 and also to glue the end flaps 10, 10 to the adjacent surfaces of flaps 8, 8 throughout the area of contact. In this manner of sealing the container it will not be necessary to use metal straps, but if the load to be packed in the container is exceptionally heavy both methods of sealing the box may be employed.

From the foregoing it will be seen that the present invention provides a shipping container formed in a very economical manner with very little waste in cutting the blanks; also, the container is strongly reinforced by a double thickness of material adjacent each of the corners at each end thereof and at the same time it is readily capable of being collapsed to take up a minimum amount of room. Thus the containers may be shipped and stored in bundles so as to take up comparatively little space and yet they are instantly available for use where reinforced containers are needed. The present container is admirably suited to the needs of a user of fibre boxes who requires a container which is adapted for carrying heavy loads and yet who does not care to go to the expense of equipping himself with

relatively expensive stapling machinery for setting up his containers. All the stapling necessary on the present container is done before it leaves the box factory.

In cutting the blanks 5, 5 it is apparent that with properly selected widths of stock none of the material will be wasted and, as to the blanks 6, 6, the only wasted portion is at the corners between flaps 9 and 10.

The equipment necessary for applying the metal straps is relatively simple and inexpensive. This equipment is of a common form and requires no description herein. Thus, by providing a box of this type particularly adapted for use with metal bands, there is made available to the packer a cheap but very strong and rugged fibre container having all the advantages of the slotted carton and none of its disadvantages. After the metal straps are drawn taut and sealed in place they lie substantially flush with the surfaces of the box and there is practically no chance of the bands slipping from position by being snagged or otherwise. With the use of the metal bands many shippers will find it desirable to have the boxes returned for reloading as the boxes can be unpacked by merely cutting the bands and after being unpacked they can be collapsed for return shipment.

The reinforced corners of the box permit the longitudinally disposed bands to be drawn very taut without danger of deflecting the corners inwardly and this is true even in cases where the goods within the box shrink somewhat during a period of storage.

While the present description sets forth a preferred embodiment of the invention, numerous changes may be made in the construction without departing from the spirit of the invention, and it is therefore desired that the present embodiment be considered in all respects as illustrative and not restrictive, reference being had to the appended claims rather than to the foregoing description to indicate the scope of the invention.

I claim:

1. A shipping container comprising a pair of blanks of fibre or paper board each forming a side wall and an upper and lower closure flap, a pair of end wall blanks having flaps on at least two opposite sides thereof secured to said side walls whereby the shipping container thus formed may be collapsed to a flat condition.

2. A shipping container comprising four flat blanks of paper or fibre board, two of said blanks being scored to provide two opposed side walls and cooperating closure flaps for the top and bottom of the container, the remaining two blanks having extensions to provide attaching and reinforcing flaps on opposite sides thereof adjacent said side walls, and means securing said attaching flaps to

the adjacent ends of said side walls whereby reinforced vertical corners are provided.

3. A four-piece fibre shipping container comprising two rectangular, scored blanks providing two opposed side wall portions and two pairs of cooperating closure flaps, two additional rectangular blanks for the remaining two opposed side walls, said blanks having flaps projecting from each side thereof, and means securing corresponding opposed pairs of said flaps to the side wall portions of said first mentioned blanks whereby reinforced corners will be provided and said container may be collapsed to a flat condition for storage and shipment.

4. A four-piece fibre shipping container comprising a pair of rectangular, scored blanks providing two opposed side wall portions and two pairs of cooperating closure flaps, a pair of additional rectangular blanks for the remaining two opposed side walls, flap extensions on one of said pairs of blanks adapted to secure said blanks together at their vertical corners whereby said vertical corners are reinforced, and additional flaps on said last mentioned pair of blanks providing additional pairs of flaps at the top and bottom of the container for cooperation with said first mentioned closure flaps.

30 5. A four-piece fibre shipping container comprising two rectangular, scored blanks providing two opposed side wall portions and two pairs of cooperating closure flaps, two additional rectangular blanks for the remaining two opposed side walls, said blanks having flaps projecting from each side thereof, means securing corresponding opposed pairs of said flaps to the side wall portions of said first mentioned blanks whereby reinforced corners will be provided and said container may be collapsed to a flat condition, and one or more metal bands disposed around said container and embracing said reinforced corners.

45 Signed at Chicago, Illinois, this 17th day of September, 1929.

CLARENCE J. GATES, JR.
